(57) **CLAIM**

We claim the ornamental design for a stud layout level, as shown and described.

DESCRIPTION

FIG. 1 is a perspective view of a stud layout level, showing our new design;

FIG. 2 is a front elevational view thereof;

FIG. 3 is a top plan view thereof;

FIG. 4 is a left side elevational view thereof in a scale of 2:1, and the right side elevational view is identical thereto;

FIG. 5 is a rear elevational view thereof; and,

FIG. 6 is a bottom plan view thereof.

(Continued)

Features in the drawings shown in dashed broken lines form no part of the claimed design.

1 Claim, 3 Drawing Sheets
